UNITED STATES PATENT OFFICE.

ISABELLE KERN WURDACK, OF NORMANDY, MISSOURI.

DESIGN FOR A ROCKING-CHAIR.

Application filed June 1, 1925. Serial No. 13,613. Term of patent 14 years.

To all whom it may concern:

Be it known that I, ISABELLE KERN WURDACK, a citizen of the United States, residing at Normandy, St. Louis County, and State of Missouri, have invented a new, original, and ornamental Design for a Rocking-Chair, of which the following is a specification, reference being had to the accompanying drawing, forming part thereof.

In the drawing Fig. 1 is a front elevation of a rocking chair showing my new design; Fig. 2 is a side elevation; and, Fig. 3 is a rear elevation.

I claim:

The ornamental design for a rocking chair, as shown.

ISABELLE KERN WURDACK.
